Assistant Examiner — Nader Abadir

(57) **CLAIM**

The ornamental design for a cookware handle as shown and described.

DESCRIPTION

1. Cookware handle

1.1 : Perspective

1.2 : Back

1.3 : Left

1.4 : Right

1.5 : Top

1.6 : Perspective

The design is a handle for use in cookware.

The broken line showing of the pan and the rivets is for the purpose of illustrating environment and forms no part of the claimed design.

The broken line portions of the handle depict portions of the handle that form no part of the claimed design.

1 Claim, 6 Drawing Sheets
